UNITED STATES PATENT OFFICE

HARVEY E. MARVEL, OF FORT WAYNE, INDIANA, ASSIGNOR TO S. F. BOWSER & COMPANY, INC., OF FORT WAYNE, INDIANA, A CORPORATION OF INDIANA

RAG-CATCHING APPARATUS FOR BEATER TUBS

Application filed June 27, 1927. Serial No. 201,566.

My present invention relates in general to improvements in paper-making equipment and has particular reference to an improved means for removing rags and other foreign material from beater tubs and transferring them to a cart, trough, or the like, for disposal.

As heretofore practiced, the rags and other foreign substances have been removed from the beater tub by more or less laborious methods requiring the services of individuals with make-shift equipment, so to speak.

One of the principal objects of the present invention is to provide mechanical means for accomplishing what has heretofore been carried out manually and in this way speed up production with increased efficiency and many other improved results.

Further objects and advantages of the invention will be described in detail as the description proceeds with reference to the accompanying drawings in which a practical embodiment of the invention is illustrated.

In said drawings:

Fig. 1 is a view in front elevation of the rag catching apparatus illustrating its application to a beater tub which is shown in section;

Fig. 2 is a view from one side of the rag catching apparatus with parts thereof shown in section;

Fig. 3 is an enlarged detail view from one side of the rag catcher cradle and some of the parts which co-operate therewith;

Fig. 4 is a horizontal section through the fluid pressure cylinder taken on the line 4—4 of Fig. 2;

Fig. 5 is a top plan view of the rag catcher showing its application to a beater tub.

Fig. 6 is a detail view in plan looking down on a portion of the cradle and the catch which co-operates therewith.

Fig. 7 is an enlarged detail view of one of the cradle fingers.

Referring now to the drawings in detail, 5 represents a beater tub which is used in the paper making industry and from which it becomes necessary to remove rags and other foreign substances at more or less frequent intervals in the course of operations. The

present invention provides means for effecting this removal of the rags from the tub 5 and depositing them upon a trough, cart, or some other receptacle suitable to receive them, with the apparatus primarily designed to accomplish this operation in a convenient and practical way. According to its preferred construction, the apparatus is intended to be lowered into the beater tub for collecting a quantity of the rags contained therein, then elevating from the tub, lifting the collected rags with it, and then moved into an unloading position preferably to one side of the tub where the rags may be unloaded upon the trough, cart, or other suitable receptacle, above referred to.

According to the embodiment of the invention which has been selected for illustrating the apparatus, the same is made up for the most part of pipe sections and fittings therefor which will cheapen the cost of producing the apparatus, making it convenient to assemble and otherwise improving its construction. With this end in view, it is proposed to make up a main supporting post 6 from two lengths, as an example, of pipe sections, the same being united end to end by a T-union or other suitable fitting 7. The lower one of these sections will extend through the head 8 of an upright cylinder 9 with the terminal thereof connected to the piston 10 which is mounted for reciprocation in the cylinder 9. The connection between the piston 10 and the lower pipe section of the post 6 preferably comprises a cup-shaped pedestal bearing 11 which is made to receive and support the end of the post and being, in turn, secured to the piston 10 by a bolt or the like 12 which extends through the center of the piston with a nut 13 on the end thereof for anchoring the same. The cylinder head 8 is made with a suitable stuffing box 14 for the post with an annular flange 15 on the inside of the head providing an abutment for the ring or flange 16 which encircles the post 95 adjacent its lower end.

Coiled around the lower end of the post between the flange 16 and the cup-shaped pedestal bearing 11 is a spiral spring 17 which will cushion the up stroke of the piston 10. The

pedestal bearing 11 is equipped with a ball thrust bearing 11' underneath so as to permit rotation of the post relative to the piston and cylinder.

5 The cylinder 9 may be secured to the outside of the beater tub by a suitable bracket 18 and, aside from the head 8, it comprises a base 19 with a plurality of connecting rods 20 radially spaced around the cylinder for connecting the head with the base and securing these parts to the respective ends of the cylinder. The base 19 is made with a central boss 21 having an internal bore 22 for the reception of the nut 13 on the end of the bolt 12 when the piston is at the limit of its down stroke in the cylinder. Projecting from one side of the base 19 is an integral extension 23 having a duct 24 which communicates with the bottom of the cylinder at one end and with its opposite end communicating with a pipe 25 for admitting water pressure or any other suitable fluid pressure into the cylinder below the piston 10. The pipe 25 is connected to a three-way valve 26 which, in turn, 10 is connected from one branch thereof to a pipe 27 from a suitable source of fluid pressure with a third branch on the valve 26 connected with a discharge pipe 28 having a T-fitting 29 therein for connecting the pipe 30 15 with the top of the cylinder, as at 21. The pipe 30 in this respect is a breather connection which relieves compression and vacuum created in the cylinder above the piston. It is to be noted that the pipe 30 makes an open 20 connection or communication at the top of the cylinder which is in no way affected by the opening and closing of the valve 26.

By opening the valve 26, water pressure, as an example, may be admitted into the cylinder 9 from the pipe 27 and the piston, in response thereto, will elevate the post 6. By closing the valve 26, water pressure may be trapped in the cylinder 9 to hold the post 6 elevated in any desired vertical position, of course within the limits of the length of the cylinder. By moving the valve lever 26 into a position to establish a communication between the pipe 25 and the discharge 28, the water may be discharged from the cylinder 9, whereupon the piston 10 will be lowered, carrying with it the post 6. In this way, the post 6 may be conveniently elevated and lowered, the purpose of which will be presently described.

55 The reciprocation, so to speak, of the post 6, is guided by a plurality of rollers 32 which are grouped about the post above the T-fitting 7. These rollers are mounted with freedom of rotation around the post by a strap bracket 33 which is connected to a pair of oblique braces 34, one of which extends downwardly across the beater tub 5 transversely thereof and is connected to the beater tub, as at 35, through the medium of a strap 36 60 which, in turn, is connected, as at 37, to a

transverse strip or rod 38 disposed across the top and secured to the opposite side thereof, as at 39. The other one of these oblique braces 36 extends downwardly substantially parallel with the side of the beater tub and is secured thereto, as at 40, through the medium of a bracket plate 41. These braces are made from rods and the ends are threaded so that they may be threaded into nipples 42 on the mounting 33 for the rollers 32 as well as to accommodate nuts for securing the same at the ends which are fastened to the sides of the beater tub. The braces 34 thus steady the post 6 and serve to support the mounting 33 for the rollers 32.

70 The rag catcher carriage is preferably made up of a boom 43 comprising a pipe section or rather, a long pipe section and a short pipe section, the latter being threaded into one branch of the T-fitting 7 and joined to the former by a T-fitting 44. The outer end of the section 43 of the boom is threaded into one end of an L-fitting 45. Secured to the L-fitting 45 by an ear 46 is a suspension brace 47, the opposite end of which terminates in a hook 48 which engages in the open end of the post 6. This suspension brace 47 serves to relieve the boom 43 of the weight carried thereby.

75 The pipe 49 is threaded to the T-fitting 44 on the boom 43 and depending downwardly therefrom is a pipe section 49 which serves as one side member of the rag catcher carriage. The opposite side member for the carriage is provided for by a pipe section 50 which is threaded to the L-fitting 45. The ends of these pipes 49 and 50 are threaded for the reception of caps 51 and 52. These caps are made with ears 53 and 54 which have openings therethrough for the reception of a horizontal rod 55.

80 The cradle structure for the rag catcher carriage, comprises a plurality of parallel rod-like members or fingers 56 each of which have their lower extremities curved outwardly to make up a cradle, so to speak, for collecting and carrying the rags. The outside ones of these fingers are shorter than the others. This applies also to the fingers next to the outside ones. The lower ends of the fingers are clamped or otherwise secured, as at 57, to the horizontal rod 55 of the rag catcher carriage and the upper ends of the fingers are secured to a horizontal rod 58, the opposite ends of which bear against the side members 49 and 50 of the carriage but are not connected thereto. A hold-back rod 59 bridges the space between the side members 49 and 50 of the carriage parallel with the rod 58 and has its opposite ends inserted through and journaled in transverse openings in the side members 49 and 50. This rod 59 is thus mounted for rotation between the side members and secured to the rod, adjacent its journaled ends, by set screws 60, are rocking

arms 61. Pivottally secured to these arms 61 are suspended levers 62 having hand holds 63. The opposite ends of these levers are provided with nose pieces 64 having dogging devices in the form of hooks which engage the rod 58 of the carriage cradle. The rod 55, to which the lower ends of the fingers are secured by the members 57, is journaled, so to speak, in the ears 53 of the caps on the ends 10 of the side members 49 and 50. Consequently, the cradle of the carriage is hingedly or pivottally connected to the carriage so that it may swing into a position shown in dotted lines in Fig. 3, to dump the load carried thereby when released by the catches as a result 15 of the pull on the levers 62.

In operating the rag catcher and considering that the carriage thereof is in an elevated position substantially as that shown in Fig. 23 1, the valve 26 will be operated to discharge the water pressure from the cylinder 9, permitting the piston 10 to move to the bottom 25 of the cylinder and, as a result, lowering the post 6 which will lower the rag catcher carriage into the beater tub where the cradle thereof will collect a quantity of the rags contained in the tub.

By reversing the position of the valve 26, the water pressure will be introduced into the 20 cylinder 9, moving the piston 10 upwardly therein, elevating the post 6, and elevating the rag catcher carriage out of the beater tub with the load carried thereby. When it has been elevated to the desired height, the valve 26 25 may be manipulated to trap the water pressure in the cylinder 9 below the piston 10 to maintain the desired elevation of the carriage. The carriage may then be swung to one side of the heater tub into a position, as an example, as shown in dotted lines in Fig. 5. When in such position, the levers 62 will be pulled which will rock the levers 61 and disconnect the catches thereof from the rod 58, releasing the cradle so that it will tilt under the influence of the load carried thereby into a position shown in dotted lines in Fig. 3, and discharge the load carried thereby. When the cradle has been relieved of the load, it may be moved into load-carrying position 50 where the catches will automatically engage the same and lock it in such position. The carriage is then ready to be swung back over the beater tub and the operation repeated.

Obviously those skilled in the art may make 55 various changes in the details and arrangement of parts as defined in the appended claims without departing from the spirit and scope of the invention, and I wish therefore not to be restricted to the precise construction herein disclosed.

I claim:—

1. In a rag catcher of the class described, a material handling carriage mounted to be lowered into and elevated from a beater tub 65 and moved into a low dumping position at der, a piston mounted for reciprocation in

one side of said tub, a material-collecting cradle comprising a plurality of spaced-apart rods each having upright comparatively long arms and lower horizontally projecting short arms pivottally mounted on said carriage to swing on a horizontal axis, a rod connecting the upper ends of said long arms, latch mechanism associated with said rod to hold the long arms in upright position and the short arms in horizontal position while rags are being carried by said cradle from the beater tub and to one side thereof, and means for releasing said latch mechanism to effect dumping of the rags by automatic swinging of the cradle on said horizontal axis. 70

2. In a rag catcher of the class described, the combination with a supporting frame, of a cradle pivoted to said frame and comprising a plurality of spaced-apart rods having lower rag catching projections and upper upright long arms, and releasable latch mechanism between said frame and the upper end of said cradle for holding the cradle upright while carrying a load and for permitting tilting of the cradle when said latch mechanism is released for the purpose of dumping the load. 80

3. In a rag catcher of the class described, the combination with a supporting frame, of fluid pressure mechanism for elevating and lowering said frame, a supplemental frame pivoted to said supporting frame and comprising an upper long arm and a lower short arm composed of a plurality of spaced-apart curved rag catching members, and releasable latch mechanism for holding the long arm in upright position while said rag catching members are carrying a load, said long arm being adapted to move away from said supporting frame when said latch mechanism is released to effect tilting of the rag catching members and the dumping of the load. 90

4. In a rag catcher of the class described, the combination with a supporting frame, of means for elevating and lowering said supporting frame and pivottally supporting the same on an upright axis for swinging movement laterally, a supplemental frame pivoted to said supporting frame for tilting movement relatively thereto on a horizontal axis, said supplemental frame having a long upright arm, latch mechanism for holding said long arm in upright position connected to said supporting frame, and a plurality of spaced-apart rag catching members connected to the lower side of said supplemental frame on that side of said horizontal axis opposite said long arm. 100

5. In a rag catcher of the class described, a supporting structure for positioning a material-handling carriage in operating relation to a beater tub, and fluid pressure means for elevating and lowering said carriage relative to said beater tub, comprising a cylinder, a piston mounted for reciprocation in 110

125

130

135

140

145

150

155

160

165

170

175

said cylinder in response to fluid pressure introduced therein, and a post connected to said piston to reciprocate therewith and to which the material-handling carriage is mounted, 10 said material-handling carriage comprising a frame structure mounted to be lowered into and elevated from the beater tub by the reciprocation of said post, and a material-collecting cradle pivotally mounted on said carriage, said cradle comprising a plurality of finger-like members mounted in fixed spaced relation and having forwardly projecting curved ends disposed below the pivot point of the cradle, and a catch on the material-handling carriage for releasably holding said cradle in load-carrying position.

6. In a rag catcher of the class described, a material handling carriage mounted to be lowered into and elevated from a beater tub, 20 a material-collecting cradle pivotally mounted on the lower end of said carriage to swing on a horizontal axis and comprising a plurality of spaced-apart horizontally projecting fingers below the pivot and a comparatively 25 long back portion projecting uprightly above said pivot, and releasable mechanism for holding the fingers of said cradle in horizontal position and the back portion thereof in upright position while carrying a load, 30 said cradle being swung automatically when released to permit the fingers to assume an upright position and movement of the back portion toward horizontal position.

7. In a rag catcher of the class described, 35 the combination with an upright post adapted to be positioned adjacent a beater tub, of a boom-like member connected to said post and adapted to swing over said beater tub, a carriage suspended from said boom-like member in an upright plane, a material-collecting and dumping cradle pivotally mounted on the lower end of said carriage for movement bodily therewith, said cradle comprising a plurality of spaced-apart downwardly and horizontally 40 projecting rag catchers, means for holding said cradle in upright position, and means for elevating and lowering said post together with the parts mounted thereon to place said cradle in position for gathering a 45 load and removing such load from the beater tub.

8. In a rag catcher of the class described, 50 the combination with an upright post adapted to be positioned adjacent a beater tub for rotation on an upright axis, of a boom extending horizontally from said post to swing over said beater tub and to one side away from the same, a carriage suspended from said boom in an upright plane, a material-collecting and dumping cradle pivotally connected to the lower end of said carriage for bodily 55 movement therewith and comprising a plurality of spaced-apart downwardly and horizontally 60 projecting rag-catching members and upwardly 65 projecting arms to form a back

rest, means for elevating and lowering said post to elevate and lower said rag-catching members into the beater tub, and means on said carriage for releasably holding said cradle in material-collecting position.

9. In a rag catcher of the class described, the combination with an upright post adapted to be positioned adjacent a beater tub, of a boom extending laterally from said post intermediate the ends thereof and adapted to swing over the beater tub and away from the same, a hydraulic motor for lifting and lowering said post together with said boom mounted thereon, said hydraulic motor affording an upright pivotal support for said post to permit swinging of said boom on the upright axis of said post, a carriage suspended from said boom, a material-collecting and dumping cradle pivotally mounted on the lower end of said carriage for tilting movement on a horizontal axis, and releasable latch mechanism for holding said cradle in upright position during the carrying of the load while said cradle is being elevated from the beater tub by the elevation of said post and swung away from the latter by the swinging of said boom on the upright axis of said post.

In testimony whereof I have signed my name to this specification on this 24 day of June, A. D. 1927.

HARVEY E. MARVEL.
